United States Patent Office

Des. 197,761
Patented Mar. 24, 1964

197,761

SHOE

Harry H. Gould, University City, Mo., assignor to Shuko Shoe Corp., Meadville, Pa., a corporation of Pennsylvania

Filed Jan. 16, 1963, Ser. No. 73,192

Term of patent 14 years

(Cl. D7—7)

FIG. 1

FIG. 2

FIG. 1 is a top plan view of a shoe embodying my new design; and

FIG. 2 is a side perspective view thereof.

The side opposite is substantially similar thereto except for the buckle.

I claim:

The ornamental design for a shoe, substantially as shown and described.
